UNITED STATES PATENT OFFICE.

PAUL H. SCHNORMEIER, OF HUBBARD, IOWA.

ILLUMINATED SIGN.

Application filed February 21, 1927. Serial No. 169,823.

The principal object of my invention is to provide an illuminated sign which shall have the advantages of signs now on the market but wherein only a minimum number of incandescent light bulbs are used.

A further object is to provide an illuminated sign having detachable and adjustable reflector brackets.

A further object is to provide an illuminated sign having adjustable brackets with removable reflecting plates.

A further object is to so arrange the reflectors in relation to the bull's eyes of the sign that an even distribution of reflected light of uniform intensity is obtained.

A further object is to provide an illuminated sign employing bull's eyes that are readily detachable from the sign housing.

A still further object of this invention is to provide an illuminated sign of reflected light which is completely inclosed against troublesome insects.

These and other objects will be apparent to those skilled in the art.

My invention consists in the construction, arrangement and combination of the various parts of the device, whereby the objects contemplated are attained as hereinafter more fully set forth, pointed out in my claims and illustrated in the accompanying drawings, in which:

Fig. 1 is a side view of a portion of one face of the sign.

Fig. 2 is an inside view of a portion of the sign with the side of the sign removed.

Fig. 3 is a cross sectional view of my complete sign ready for use and is taken on line 3-3 of Fig. 1.

Fig. 4 is a perspective view of the adjustable reflector frame with a portion cut away to more fully illustrate its construction.

Fig. 5 is a side sectional view taken on line 5-5 of Fig. 1 and shows the means for securing the bull's eyes in the face of the sign.

Fig. 6 is a front view of a portion of the face of the sign showing the construction of the aperture into which the bull's eye is secured.

Fig. 7 is a top sectional view taken on line 7-7 of Fig. 6 and more fully illustrates a means for receiving and holding a bull's eye in one of the apertures.

There are a few signs now on the market that use reflected light for illumination by passing it through openings. These signs

are open and receive harmful foreign matter as well as attracting and receiving various kinds of insects into the sign housing which soon render the sign inoperative. Their reflectors are nonadjustable and are subject to distortion consequential to handling the sign in transportation, installation, or maintenance. Their reflectors farthest from the light source are dimmer than the reflectors close to the incandescent light bulb. I have overcome all these disadvantages by providing an inclosed sign with bull's eyes designed to receive reflected light from adjustable and movable mirrors that are so designed and arranged as to deliver the same amount of light power to each bull's eye.

The numeral 10 designates a sign housing having the hinged sides or faces 11 and 12. The wall 13 divides the housing into two separate compartments and thereby creates a two-faced sign. On the outside of each face may be painted letters 14 or other characters as are desired. These characters are studded with bull's eyes 15 arranged in somewhat close association in the outline of the letters. These bull's eyes are each permanently secured in a case 16 having the lugs 17. The lugs 17 of each case are designed to enter the notches 18 respectively of one of the apertures 19. By rotating the bull's eye a portion of a revolution the lugs engage the back of the depressed portion 20 adjacent each notch 18. This construction is fully illustrated in Figures 5, 6, and 7.

By this construction it will readily be seen that if illumination is produced back of the bull's eyes the complete sign will be illuminated. Directly back of each bull's eye and secured to the wall 13 by suitable means is an ordinary split ball socket 21. The numeral 22 designates a ball in each one of the split sockets and secured to which is a reflector frame 23. This construction permits the reflector frame to be moved and held at various angles relative to its respective bull's eye. The top portion of each of these frames is open as shown in Fig. 4 thus allowing a small mirror 24 to be inserted into the frame. Mounted to the bottom and inside of the housing 10 are incandescent light bulbs 25.

If the frames 23 are at the proper angle they will intercept the light rays from the incandescent light bulbs and reflect them laterally to their respective bull's eyes. The light rays emanating from each of the bull's eyes, gives the appearance at 110

a distance of a separate source of illumination back of each bull's eye. I find that by this arrangement a single incandescent light bulb is sufficient for one letter or character. In order that the bull's eyes farthest from the incandescent light bulb will have the same brilliancy as those closer to the incandescent light bulb I have placed the reflectors closer to the bull's eyes that are at a distance from the incandescent bulb. This arrangement is illustrated in Fig. 3 and it will be noted that the distance between the reflector and the bull's eye is in ratio to the distance of the reflector from the light bulb. This gives the complete sign a uniform appearance and perfects its displaying qualities. To accomplish the placement of some of the reflectors closer to their respective bull's eyes than other reflectors, I have used split ball sockets as shown in Fig. 3 that extend a greater distance from the wall. In order that these split ball sockets will successfully engage their respective balls, the rivet 26 may be used to more securely bind the two split portions of each split ball socket together. Another advantage of having the reflectors at various distances from the wall 13 is that they do not conflict one with the other in intercepting the rays from the light bulb. This makes it possible to have a very narrow housing. By having the frames 23 open at their top, broken mirrors may be replaced therein very readily and easily. The bull's eyes may be of clear or colored glass and their removable feature makes it possible to change the color of the bull's eyes to suit the occasion. All signs sooner or later must be cleaned and painted and the adjustability of the reflecting frames makes this possible without danger of getting the sign out of order. It is merely necessary to swing the side of the sign open on its hinges and properly adjust the frames so that the light will be directed properly to the various bull's eyes. This adjustability of the reflecting frames also facilitates the adjustment of the complete sign when it is installed. The numeral 27 designates openings in the wall 13 so that the reflector frames on both sides of the wall may be adjusted from one side. It will readily be seen that I have produced a sign which is economical in manu-

facture and use and which will appear, when in use, at a distance as a sign wherein the letters are composed of a plurality of incandescent light bulbs.

Some changes may be made in construction and arrangement of my device without departing from the real spirit and purpose of my invention and it is my intention to cover by my claims any modified forms of structure or use of mechanical equivalents which may be reasonably included within their scope.

I claim:

1. In a device of the class described, a sign housing having a hinged side, said housing having openings in each of its two sides in the outlines of the letter or character strokes to be displayed, a webbing in said housing and between said two sides, a lamp on each side of said webbing, and adjustable reflectors secured to each side of said webbing for receiving and diverting light rays from said lamps to said openings; said webbing having openings for permitting the adjusting of said reflectors from one side of the said housing.

2. In a device of the class described, a sign housing having two hinged sides, said sides each having openings in the outlines of the letter or character strokes to be displayed, a webbing in said housing and between said sides, a plurality of ball sockets secured to each side of said webbing, a ball in each of said sockets, a reflector secured to each ball, a lamp on each side of said webbing; said webbing having openings for permitting the adjustment of all of the reflectors in the housing from one side thereof.

3. In a device of the class described, a housing having a hinged side, said housing having openings in each of its two sides in the outlines of the letter or character strokes to be displayed, a crystal for each of said openings, a means for quickly attaching and detaching said crystals, a webbing in said housing between said two sides, a lamp on each side of said webbing, and adjustable reflectors secured to each side of said webbing for receiving and diverting light rays from said lamps through said crystals; said webbing having openings for permitting the adjustment of said reflectors from one side of said housing.

PAUL H. SCHNORMEIER.
